VENDING MACHINE CONSTRUCTION

Gilbert J. Scofield, Loudonville, N. Y.

Application December 8, 1934, Serial No. 756,663

11 Claims. (Cl. 312—65)

This invention relates to a vending machine construction.

One of the objects of this invention is to provide a vending machine which is simple in construction and thoroughly efficient and practical in operation. Another object is to provide a construction of the above nature which is durable and which can withstand long continued use. Another object is to provide a construction of the above nature which is inexpensive to construct, pleasing in appearance and which takes up but slight space when installed. Another object is to provide a construction of the above nature which can be easily operated and in which the delivery of an article is assured after payment of a legitimate coin into the machine. Another object is to provide a construction of the above nature which accommodates ample supplies of different articles. Another object is to provide a construction of the above nature which can be operated to select one of several different kinds of merchandise and deliver the same. Another object is to provide a construction of the above nature in which a single operating part effects both selection and delivery of the article purchased. Another object is to provide a construction of the above nature which necessitates payment of a legitimate coin before selection or delivery can be effected. Another object is to provide a construction of the above nature in which double delivery, after the payment of a single coin, is effectively prevented. Other objects will be in part apparent and in part pointed out hereinafter.

The invention accordingly consists in the features of construction, combinations of elements, and arrangements of parts as will be exemplified in the structure to be hereinafter described and in the scope of the application of which will be indicated in the following claims.

In the accompanying drawings in which is shown one of the various embodiments of my invention,

Figure 1 is a front elevation of the vending machine;

Figure 2 is an enlarged sectional view taken along the line 2—2 in Figure 1;

Figure 3 is an enlarged fragmentary vertical sectional view taken along the line 3—3 of Figure 1;

Figure 4 is a horizontal sectional view taken along the line 4—4 in Figure 3;

Figure 5 is an enlarged sectional elevation showing certain of the operating parts of my construction; and

Figure 6 is a fragmentary sectional elevation showing the coin detector and certain other operating parts of my construction;

Figure 7 is a perspective view of the lower portion of one of the merchandise containers of the vending machine.

Similar reference characters refer to similar parts throughout the several views of the drawings.

As conducive to a clearer understanding of my invention, it might here be pointed out that numerous difficulties are encountered in providing a vending machine which is capable of vending a number of articles differing in quality and/or shape. Such machines generally necessitate the provision of a number of coin-entry slots, operating levers, and delivery chutes and are accordingly bulky and ill appearing. A further difficulty is encountered in effectively preventing the delivery of more than one article for the payment of a single coin and still further difficulties are encountered in combining with such machines suitable apparatus for detecting and rejecting counterfeit coins, slugs and the like. Another object of this invention is to obviate such difficulties in addition to many others.

Generally, my vending machine is comprised of an enclosure, generally indicated at 10 in Figure 1, through which extends an operating knob 11 which controls the mechanism disposed within the enclosure. Extending upwardly of and secured to enclosure 10, I provide preferably a cylindrical, transparent casing 12 within which are displayed and rotatably mounted a number of containers 13. A top portion 14 rests upon the top of casing 12 and is secured thereon in a manner to be more fully pointed out hereinafter. A coin-entry slot 15 is suitably positioned in enclosure 10 and a delivery pocket 16 and a coin-return pocket 17 are suitably disposed on the exterior of the enclosure. A coin drawer 18 conveniently extends through the front of enclosure 10 and is positioned therewithin to receive the coins deposited into the machine.

As is more clearly shown in Figure 3, enclosure 10 is comprised of a bottom casing 10a and an upper casing 10b which is provided with a shoulder 10c. Thus, casing 10b may be readily placed upon the top of casing 10a and secured thereto in a manner to be later described. A slotted ring 19 is suitably secured to the top of casing 10b and this ring receives glass cylinder 12. A supporting part 20 (Figures 1 and 3) is also secured to the top of casing 10b and includes a suitable cushioning element 20a (Figure 3) which presses

against glass cylinder 12 to hold the cylinder in its assembled position. Top 14 is provided with a flange 14a in which is cut a slot 14b which receives the top of glass cylinder 12, glass cylinder 12 being preferably secured to flange 14a in any suitable manner. Thus top 14, glass casing 12 and casing 10b are secured together as a unit.

Still referring to Figure 3, a partition 10d is secured to the side walls of casing 10a and this partition supports a frame which is generally indicated at 21 (see also Figures 4 and 6) the frame being suitably secured to partition 10d as by screws 21a. Frame 21 is preferably a casting and is provided with a number of suitable bosses and bores which support most of the operating parts of the machine, as will be described hereinafter. It will thus be seen that a distinct advantage is gained in providing a unitary support on and in which is assembled a large proportion of the operating mechanism.

As is best seen in Figure 3, frame 21 includes a boss 22 and a journal 23. Boss 22 is provided with a bore in which is disposed a support shaft 24 which is secured against rotation by means of a pin 25 extending through both the boss and the shaft. Rotatably disposed on shaft 24 and revolvably borne in journal 23, I provide a hollow shaft or sleeve 26. Secured to sleeve 26 and rotatable therewith are a pair of spiders 27 and 28, spider 27 including a portion 27a which acts as a thrust-bearing against the top of journal 23 and accordingly supports sleeve 26 in its proper operative position. Spider 28 includes a top portion 28a from which extend downwardly a suitable number of webs 28b (Figure 2). Webs 28b extend from hub portion 28c (Figure 3) to side walls 28d which are preferably flat and have formed on the exterior sides thereof slots or channels 28e. A screw 29 extends through the upper portion of hub 28c and secures spider 28 to sleeve 26 (see Figure 3). Spider 27 is accordingly likewise provided with a top 27a, webs 27b, a hub 27c, and side walls 27d, the side walls having slots or channels 27e substantially similar to channels 28e.

As has been pointed out above, containers 13 are disposed within glass casing 12. As is more clearly shown in Figure 2, these containers are provided with support brackets 13a, on the ends 50 of which are secured plates 13b suitably formed to engage spiders 27 and 28 with a sliding fit in slots or channels 27e and 28e (see Figure 3). Thus, it may be seen that containers 13 may be readily installed in or removed from their operative engagement with the spiders. By referring to Figure 2, it may also be seen that by making the containers readily detachable from the spiders, containers of different sizes may be used and accordingly articles of different quality or 60 size may be accommodated.

In Figure 3, a delivery chute 30 is indicated by a broken line and the top of this delivery chute is always positioned adjacent one of containers 13 so as to receive articles 31 ejected therefrom in a manner to be described hereinafter. Delivery chute 30 communicates with delivery pocket 16 (Figure 1) from which the delivered article may be readily retrieved.

It may now be seen that shaft 24 (Figure 3) supports sleeve 26 which in turn supports the spiders and containers which rotate with the sleeve. Shaft 24 preferably extends above sleeve 26 and into a bore 14c suitably formed in a boss 14d extending from top 14. A lock 32 extends through top 14 and has secured to the operating mecha-

nism thereof a lever or arm 33 which engages shaft 24 in a slot 24a (not shown) formed therein. Thus, upon insertion of the proper key in lock 32, arm 33 may be swung from its engagement with shaft 24, thus permitting the unit comprised of top 14 and accordingly glass casing 12 and casing 10b to be lifted bodily from the top of casing 10a, thus to permit access to the containers and the operating mechanism. Similarly when the containers have been refilled, the mechanism 10 adjusted or repaired, etc., the above-mentioned unit is replaced and arm 33 is swung into engagement with shaft 24, hence securely locking the machine against access from its exterior.

With reference to Figure 6, coin drawer 18 is slidably disposed within the space provided between partition 10d and the bottom of casing 10a. Suitably secured to the top of partition 10d is a hinge bracket 34 which pivotally supports a latch generally indicated at 35. Latch 35 includes an ejector arm 35a, a catch 35b, and an operating arm 35c. Arm 35a and catch 35b project through partition 10d into coin drawer 18 in the path of a lug 18a secured to a side of the coin drawer. Arm 35c projects upwardly from partition 10d into the path of a push rod 36 which is slidably mounted in a sleeve 37 secured to frame 21. Push rod 36 includes an upwardly extending arm 36a, the top of which is exposed when casing 10b is removed. Accordingly, when arm 36a is pushed inwardly of casing 10a, or to the right as viewed in Figure 6, latch 35 is pivoted so that catch 35b moves out of the path of lug 18a and ejector arm 35a abuts lug 18a forcing coin drawer 18 partially out of casing 10a where it may be readily grasped for further withdrawal as desired. A spring 38 is secured to frame 21 and arm 35 and constantly urges latch 35 into its locking position. Thus, upon the closing of coin drawer 18, lug 18a forces catch 35b upwardly until the drawer is completely closed, whereupon the catch is forced downwardly by spring 38 and lies in front of lug 18a to prevent withdrawal of coin drawer 18.

As is most clearly shown in Figure 3, frame 21 includes a portion 21a in which is journaled a shaft 39. Externally of portion 21a and secured thereto is a plate 40 or the like having extending therefrom a shoulder 40a. Shaft 39 extends through plate 40 and through an opening 50 in casing 10b and has mounted thereon an operating knob or handle 41, which abuts against shoulder 40a. Knob 41 is secured to shaft 39 by means of a pin 42 or the like and accordingly rotation of knob 41 rotates shaft 39. On the other end of shaft 39, I provide a clutch, generally indicated at 43.

As is more clearly shown in Figure 4, clutch 43 is comprised of a part 44 keyed to shaft 39 (Figure 3) and has formed on the opposite sides 60 thereof a number of jaws 44a and 44b, preferably two jaws on left side of clutch part 44 and four jaws on its right side. Clutch part 44 (Figure 3) accordingly rotates with shaft 39. Clutch 43 (Figure 4) also includes parts 45 and 46, both of which are respectively provided with jaws 45a and 46a which engage jaws 44a and 44b respectively on clutch part 44. However, jaws 44a (Figure 4) and 45a engage each other only upon counterclockwise rotation of knob 41, and jaws 70 44b and 46a engage each other only upon clockwise rotation of knob 41. Journaled in clutch part 44 and extending therefrom is a stud shaft 47 (Figure 3) and on the free end of this stud shaft there is keyed a bevel gear 110. Disposed be- 75

tween bevel gear 110 and clutch part 45 is a spring 49 and this spring constantly urges clutch part 45 into engagement with clutch part 44, clutch part 45 being slidably mounted on stud shaft 47. However, upon clockwise rotation of knob 41, jaws 44a and 45a override partially compressing spring 49 (see Figure 4), and thus do not impart rotation to stud shaft 47 and accordingly bevel gear 110.

Referring again to Figure 3, a bevel gear 50 is suitably secured to sleeve 26 and this bevel gear meshes with bevel gear 110 and is rotated thereby upon counterclockwise rotation of operating knob 41. Hence upon counterclockwise rotation of knob 41, jaws 44a on clutch part 44 engage jaws 45a on rotating clutch part 45 which in turn rotates stud shaft 47 to which clutch part 45 is keyed. The rotation of stud shaft 47 imparts rotation to bevel gear 110 which, through its meshed relationship with bevel gear 50, causes the rotation of sleeve 26 and accordingly spiders 27 and 28 and the containers 13 which are secured thereto. Clockwise rotation of knob 41 (Figure 3) does not cause a rotation of sleeve 26 because jaws 44a and 45a merely override and force clutch part 45 out of engagement with clutch part 44, at the same time compressing spring 49.

As has been pointed out, I have provided a number of containers 13 which may differ in size and shape in order to accommodate not only a large number of vendable articles but also different kinds of articles. Accordingly when the purchaser wishes to select one of several kinds of articles he turns knob 41 in a counterclockwise direction to rotate the containers as pointed out above. However, I have found it preferable to aid selection by providing mechanism which accurately places the selected container in a delivery position with respect to delivery chute 30. To this end, as is more clearly shown in Figures 3 and 4, there is secured preferably to the bottom of sleeve 26 a selector wheel, generally indicated at 51, from the periphery of which a suitable number of arcuate portions 51a are cut out. These arcuate portions 51a preferably correspond in position and number to containers 13 and accordingly the positioning of one arcuate portion determines the delivery position of its corresponding container.

To positively position one of arcuate portions 51a and accordingly one of the containers, I provide, as is better shown in Figure 4, an arm 52 which is pivotally mounted on a lug 21b extending from frame 21. A roller 53 is rotatably mounted on arm 52 and is of a suitable diameter to attain a substantially close engagement with any one of arcuate portions 51a. Preferably the radius of roller 53 is greater than that of arcuate portion 51a to provide a clearance between the roller and the selector wheel as illustratively shown in Figure 4. The provision of this clearance enables the roller to ride over the tooth-like portions of selector wheel 51 during the operation thereof and renders the selecting operation more rapid and accurate as will be pointed out hereinafter. A spring 54 is suitably secured to the free end of arm 52 and to frame 21 and accordingly constantly biases roller 53 into engagement with selector wheel 51. Thus, as shaft 26 is rotated, as pointed out above, selector wheel 51 likewise rotates and forces roller 53 to ride over the tooth-like portions of selector wheel 51 between adjacent arcuate portions 51a thereof, thus positively selecting a predetermined container by engaging in an arcuate portion. Se-

lector wheel 51 (Figure 4) has a clockwise rotation and, to prevent a counterclockwise rotation thereof, there is provided a leaf spring 55 suitably secured to a lug 56 extending upwardly from frame 21. Thus, the end of spring 55 abuts against the teeth on selector wheel 51 to prevent counterclockwise rotation thereof.

During the clockwise rotation of sleeve 26 and accordingly containers 13, the assembly of containers attains substantial momentum. To provide for the rebound, engendered by the inertia of the containers, upon the sudden halting of rotation of the containers by the action of roller 53 and selector wheel 51, which rebound would tend to separate jaws 44a and 45a, a spring 57 is provided. This spring is secured at one end to clutch part 44 and at its other end to clutch part 45, thus tending to keep the respective teeth or jaws thereof in mesh and resist the above-mentioned rebound. Thus, when selector wheel 51 is actuated to a stop position, the forces resulting from the inertia of the containers 13 is absorbed by spring 57 and stop spring 55. Accordingly, containers 13 are positively aligned for delivery of the article selected.

From the above it will now be seen that a predetermined selection of any one of the containers may be positively and easily accomplished by turning operating knob 41 (Figure 3) in a counterclockwise direction. In other words, the vending machine is now conditioned for delivery of the selected article.

By the provision of a number of containers 13, selectable within a transparent casing such as casing 12, a purchaser is assured a return of an article upon payment therefor in that if the container selected should happen to be empty such condition is clearly visible and he can accordingly select another container before effecting delivery. However, if the purchaser fails to notice the empty condition of container 13 and attempts to effect delivery of a selected article, other means are provided which render such attempted operation impossible thus giving the purchaser still another chance to receive an article for his deposited coin, all as will be more fully described hereinafter.

Referring now to Figure 3, it will be seen that clutch part 46 is preferably a unit having integrally related therewith a collar portion 46d, a reduced portion 46b, and a collar 46c, the unit being rotatably mounted on shaft 39 and collar portion 46c abutting against the interior side of frame portion 21a. On collar portion 46d there is formed a cam 47. A disgorging lever 48 is mounted to pivot about a pin 49 which is secured in a suitable boss extending from frame 21. The lower end of disgorging lever 48 rotatably mounts a cam roller 50 while on the upper end thereof, there is secured a disgorging plate 48b. As is more clearly shown in Figure 7, disgorging plate 48b is of substantial area and, as shown in Figure 3, is positioned so as to force one of articles 31 out of a container 13 upon disgorging arm 48 being pivoted. A spring 52 (Figure 3) is secured to portion 21a of frame 21 and constantly biases disgorging lever 48 away from the selected container 13 by bearing against a pin 48a extending from lever 48.

Delivery of an article from container 13 (Figure 3) by disgorging lever 48 is effected by a clockwise rotation of knob 41 subsequent to its counterclockwise selective rotation. Upon such clockwise rotation, jaws 44a and 45a of clutch

parts 44 and 45 (Figure 4) respectively are forced out of mesh and override, whereas jaws 44b and 46a of clutch parts 44 and 46 respectively are forced into mesh and accordingly clutch part 46 is rotated in a clockwise direction. As this rotation continues, cam 47 (Figure 3) rotates and cam roller 50 rides over its surface, thus pivoting disgorging lever 48 so as to swing disgorging plate 48b into an opening 13b in the 10 selected container 13 and force one of articles 31 therefrom into delivery chute 30. The clockwise rotation of knob 41 is continued preferably through substantially 90° at which point the rotation is positively terminated by the abutment 15 of a pin 53 (Figure 4) against a stop 55 which extends from frame 21. When pin 53 abuts stop 55, delivery of article 31 has been effected.

After such delivery, knob 41 automatically returns to its neutral position upon its release 20 from the operator's hand. This automatic return is effected by means of a spring 58 (Figure 4) which is secured at one end to a lug 59, extending from frame 21, and at its other end (Figure 3) to a pin 60 projecting from reduced 25 portion 46b. During this automatic return the jaws in clutch part 44 (Figure 4) and the jaws in clutch part 45 would abut so vigorously as to possibly become separated through the rebound were it not for spring 57 which holds the two 30 clutch parts in question together. Disgorging lever 48 is also automatically returned by the action of spring 52 against pin 48a extending from the lever. Thus all parts are automatically conditioned for the next operation.

The neutral position to which knob 41 (Figure 3) is automatically returned is determined by the position of clutch part 45. Clutch part 44 rotates with knob 41 during the delivery operation of the knob. Accordingly, the return rotation of the knob and clutch part 44, which is effected by spring 58 (Figure 4), is limited by the engagement between the teeth on clutch part 44 and the teeth on clutch part 45. While clutch part 45 can be rotated in counter-clockwise direction as viewed in Figure 4, it must in doing so rotate sleeve 26 on which the containers are mounted, and also rotate selector disc 51 against the bias of the spring urged roller 53. The inertia of the containers and the bias of spring urged roller 53 are sufficient to counteract the force or torque of the counter-clockwise rotation of clutch part 44 at the time its teeth engage the teeth on clutch part 45, and accordingly clutch part 45 stops the motion of clutch 55 part 44 and accordingly knob 41, stopping the knob in its neutral position.

In order to prevent the delivery of more than one article for a single coin, there is secured to the shaft portion 41a of knob 41 (Figure 3) and 60 rotatable therewith a disc 61 which, as is more clearly shown in Figure 5, is provided with toothed segments 61a preferably spaced equidistantly about its periphery, thus providing smooth circumferential portions 61b between the toothed segments. Thus, disc 61 constitutes a ratchet. Projecting from frame 21 is a pin 62 which pivotally supports a pawl 63. A spring 64 is secured at one end to pawl 63 and at its other end to a pin 65 extending from frame 21. 65 Pins 62 and 65 are preferably so related to frame 21 that a line drawn through their axes extends through the axis of shaft 39, pawl 63 thus being held by spring 64 in a dead-center position with respect to shaft 39 and the point thereof 70 being spaced slightly from circumferential por-

tions 61b. As pawl 63 is pivotable, it will ride over toothed segments 61a upon rotation of ratchet 61 in either direction but, when the point of pawl 63 is engaged in the teeth of any one of the toothed segments during rotation in one direction thereof, reverse direction cannot be imparted to the ratchet until the ratchet has been sufficiently rotated to completely disengage the pawl from the toothed segment with which it is in engagement. In other words, during 10 counterclockwise rotation of the ratchet (Figure 5) which is the direction of selection, clockwise or delivery rotation cannot be commenced until selection is completed. Thus, the risk of jamming the mechanism is precluded for the reason 15 that, immediately after pawl 63 becomes disengaged from ratchet 61, selector roller 53 (Figure 4) passes over one of the selector wheel teeth and spring 54 completes the rotation of the selector wheel by forcing roller 53 into the next 20 concavity 51a to place one of containers 13 in delivery position. As this action is very rapid, clockwise or delivery rotation of knob 41 cannot be effected rapidly enough to jam disgorging plate 51 between adjacent containers 13. 25

When ratchet 61 (Figure 5) is turned in clockwise or delivering direction, pawl 63 is pivoted in the opposite direction by the ratchet teeth and becomes engaged therewith, thus precluding counterclockwise rotation until delivery is effected. Accordingly, it may now be seen that when pawl 63, as viewed in Figure 5, is pivoted clockwise by the counterclockwise selecting direction of rotation of ratchet 61, delivery or clockwise rotation is prevented until the pawl 35 has cleared the ratchet teeth. And conversely, when the pawl is pivoted in counterclockwise direction by the clockwise or delivery rotation of ratchet 61, counterclockwise rotation of ratchet 61 is precluded until delivery is effected, thus preventing double delivery by the restoration of certain locking mechanisms as will be described hereinafter.

In order to prevent the selection and delivery of an article from the vending machine without the deposit of a coin therein, a coin-controlled locking mechanism is preferably provided. With reference to Figures 3 and 5, a locking disc 66 is secured to and rotates with portion 41a of knob 41. As is better shown in Figure 5, locking disc 66 has a suitable number of preferably concave 50 portions 66a equi-distantly disposed about the periphery of the disc. When operating knob 41 (Figure 3) is centered, one of concave portions 66a (Figure 5) is positioned contiguous to a ball 55 67 which, as is better shown in Figure 6, is disposed within a cavity 68 in a housing 69. When ball 67 is in the bottom of cavity 68 it lies within concave portion 66a and thus, while preferably allowing partial pivotal rotation of locking 60 disc 66 for certain purposes to be set forth later, prevents such rotation thereof as would permit selection or delivery.

When ball 67 is moved upwardly in cavity 68, selecting or delivering rotation of locking disc 65 66 may be effected. In order thus to displace ball 67 out of its locking relationship with locking disc 66, there is provided a coin-operated arm 70 (Figure 6) which is pivotally mounted on a pin 71 extending from frame 21. Arm 70 70 includes a portion 70a on which ball 67 rests and which is disposed within a slot 69a (Figure 5) in housing 69. Thus, upon clockwise pivoting of arm 70, portion 70a thereof raises ball 67 in cavity 68 thus to permit rotation of locking disc 75

66 and accordingly operation of the vending machine. Preferably a cotter pin 72 or the like extends through housing 69 and prevents portion 70a of arm 70 from forcing ball 67 completely out of cavity 68.

5 In the upper end of coin-operated arm 70 (Figure 6) is a coin reception plate 70b or the like in which legitimate coins drop to cause the pivoting of arm 70 by overbalancing the same and accordingly effect the unlocking of lock disc 66 as already described. Arm 70 thus overbalanced pivots, and locking ball 67 is maintained out of locking engagement with locking disc 66.

10 To assure the return of arm 70 into locking position there is provided a pin 73 (Figure 3) extending from collar 46c. When knob 41 is rotated in delivery or clockwise direction, collar 46c is likewise rotated thus causing pin 73 to swing upwardly against the inclined surface of a link 74 which is free to swing a certain distance in one direction on coin arm pin 71. Link 74 is thus free to rotate in a counterclockwise direction about pin 71 but cannot swing in a clockwise direction thereabout past the point where its upper surface is parallel to the axis of shaft 39. Therefore, as may be more clearly seen in Figure 4, when spring 58 effects the automatic return of reduced portion 46b and accordingly collar 46c, as pointed out above, pin 73 (Figure 3) is swung 15 downwardly on link 74 (Figure 4) which causes a rotation of pin 71 in a clockwise direction. This rotation of pin 71 returns coin arm 70 into its locking position, the dotted line position shown in Figure 6, thus permitting locking ball 67 to engage 20 lock disc 66 in one of the concavities 66a thereof.

25 In order to prevent coin arm 70 from rebounding into an unlocking position, a counterweight 75 is secured to one end of pin 71. In case the counterweight is not effective to prevent such rebound, a coin-arm stop 76 (Figure 6) is provided. Stop 76 is pivotally mounted on a pin 77 secured to frame 21 and during the upward or locking movement of coin arm 70, the extreme end 76c of coin-receiving plate 70b contacts the inclined portion 76a of stop 76 to pivot the stop away from coin plate 70b. When end 76c passes the uppermost extent of inclined portion 76a, stop 76 swings back toward arm 70 and allows end 76c to pass in a groove 76b in the stop. The pivotal return of stop 76 to its normal position thus sufficiently absorbs the rebound of coin arm 70.

30 Stop 76 has an additional function. In the event that an attempt is made to effect delivery from the vending machine by tipping it backwardly or rocking it to cause arm 70 to pivot, a weight 78 is pivotally mounted on frame 21 and abuts against an arm 76c extending upwardly from stop 76 causing the stop to pivot, in effect, in a clockwise direction thus to cause a grooved portion 76d thereof to contact the end of coin arm 70. Hence arm 70 is prevented from becoming overbalanced and accordingly unlocking the operating mechanism. A pair of abutments 79 and 80 extend from frame 21 and are so disposed with 35 relation to pivoted weight 78 as to prevent its displacement from operative position by violent tipping of the vending machine.

40 In the event that weight 78 or stop 76 become 45 inoperative, fraudulent unlocking of the vending machine by tipping it backwardly is further prevented by means of a ball 95 (Figure 3) which rides on an inclined extension 96 of frame 21. As the machine is tipped backwardly, extension 96 approaches the horizontal and becomes oppositely inclined so as to permit ball 95 to roll readily over

5 extension 96 and thus become disposed within cavity 66a of lock 66 and so lock the machine. A cotter pin 97 or the like is preferably provided to prevent ball 95 from falling off of extension 96 when the machine is in normal position.

5 An additional safety device is provided to prevent the delivery of an article without the insertion of a proper coin. As shown in Figure 3, a leaf-spring 101 or the like is suitably secured to the rear of each of containers 13, the bottom of 10 this spring being spaced from the delivery port 13d of container 13 and substantially adjacent thereto. Spring 101 has sufficient tension to prevent one of articles 31 from falling out of the container when the machine is tipped over backwards 15 and is not strong enough to hinder the legitimate delivery of one of the articles.

20 Referring now to Figure 7, it may be seen that each of containers 13 is provided with an opening in one wall thereof, this opening being 20 defined by wall portions 13c. Slidably disposed within container 13 is a weight, generally indicated at 100, this weight being comprised of a body portion 100a and a projecting portion 100b. Between portions 100a and 100b are slots 100c 25 or the like and into these slots wall portions 13c of container 13 fit. Thus, weight 100 is free to slide up and down within container 13 but cannot be displaced laterally thereof. Weight 100 has two functions. When placed upon the top of 30 a pile of articles 31 (Figure 3) it forces the articles downwardly so that the bottom-most article is always in a delivery position where disgorger plate 48b can effect delivery of the article by passing between walls 13c (Figure 7) and thus 35 force one of the articles out of the container through opening 13d (Figure 3) in the bottom thereof. The other purpose of weight 100 is to prevent the delivery operation of the vending machine when the selected container is empty. 40 Referring to Figure 7 it may be seen that when container 13 is empty, weight 100 lies on the bottom of the container so that projecting portion 100b of the weight lies in the path of disgorger plate 51. Thus, when disgorging lever 48 is swung 45 by delivery operation of the machine, plate 48b abuts against projection 100b to prevent its further disgorging motion and accordingly prevents the restoration of the locking mechanism which would ensue were complete disgorging motion imparted to disgorging lever 48. Thus, the purchaser will have an opportunity to select another container without the insertion of an additional coin, as arm 70 (Figure 6) remains in unlock- 50 ing position.

55 In order to prevent the operation of the vending machine by counterfeit coins, slugs or the like, a coin detecting device, generally indicated at 81 in Figure 6, is preferably provided. Coin detector 81 comprises a scavenger, generally indicated at 82, and a weight tester, generally indicated at 83. As certain of the specific details of scavenger 82 and weight tester 83 comprise part of the subject matter of my copending application, Serial Number 752,051, only certain 60 details thereof will be described.

65 Scavenger 82 includes a scavenger plate 84 which is pivotally mounted on a bracket 85 suitably secured to frame 21. A spring 86 biases scavenger plate 84 in a clockwise or closed direction with respect to bracket 85 (Figure 5) and the bottom of plate 84 is provided with a track portion 84a which forms a coin track over which 70 coins roll after insertion through coin slot 15 (Figure 6). Thus legitimate coins and various 75

types of metallic slugs after insertion through coin entry slot 15 roll over track 84a which is preferably inclined, but bits of paper, leather slugs, and the like will not traverse the scavenger 5 but will become lodged on coin track 84a.

In order to prevent such refuse from jamming the coin track, scavenger operating mechanism is preferably provided, to this end, as is best shown in Figure 5, an arm 87 is pivotally mounted 10 on a pin 88 secured to and extending from frame 21. A roller 89 is rotatably mounted on a pin 90 secured to and extending from arm 87, and this roller rides in one of concavities 66a on locking disc 66. The free end of arm 87 supports a floating link 91 or the like which is held in proper 15 position on arm 87 by a pair of guides 92 and 93 which are secured to a plate 94, this plate preferably being a part of bracket 85. Floating link 91 includes an arm 91a which in normal 20 inoperative position is positioned beneath a projection or arm 84b of scavenger plate 84. Assuming that a piece of paper or a leather slug has been inserted in the machine and assuming that it becomes lodged in scavenger 82, an attempt 25 will then be made to operate the vending machine by turning operating knob 41 (Figure 3) in one direction or the other. As the leather slug has not caused the retraction of locking ball 67 from lock disc 66, the machine is still locked 30 and accordingly only a partial rotation of knob 41 in one direction or the other is possible. This partial rotation, however, will cause roller 89 (Figure 5) to ride up one side or the other of concavity 66a and accordingly jiggle arm 87 as 35 knob 41 is turned. When arm 87 is raised, floating link 91 is kicked upwardly and its arm 91a forces scavenger arm 84b upwardly causing scavenger 84 to open into the dotted line position (Figure 5) and drop the leather slug or the like 40 into the coin return chute 94 (Figure 6). When floating pin 91 attains its maximum upward position, as indicated by the dotted line position in Figure 5, its arm 91a becomes disengaged from scavenger arm 84b thus permitting spring 86 45 (Figure 6) to close scavenger plate 84. As this action is very rapid, scavenger plate 84 is open just long enough to reject the leather slug and not long enough to cause the rejection of a legitimate coin should such coin be inserted immediately 50 after the attempted operation of the vending machine.

As weight tester 83 (Figure 6) detects and rejects overweight and underweight slugs and returns them to pocket 17 by way of return chute 55 94, it will be seen that the vending machine can only be conditioned for operation by means of a legitimate coin.

It will now be clear that upon the insertion of a proper coin, such coin will pass through detecting 60 device 81 (Figure 6) and fall upon coin lever 70. Coin lever 70 thus overbalanced pivots and forces locking ball 67 out of engagement with lock disc 66. Lock disc 66 (Figure 3) thus being unlocked, rotation of knob 41 in either direction is 65 now possible. If it is desired to select a container 13 different from the one already in delivery position, knob 41 is turned in a counter-clockwise direction. Upon the knob being so turned, shaft 39, which is keyed to clutch part 44, 70 causes clutch part 44 and accordingly clutch part 45 to rotate. This rotation is thence imparted to stud shaft 47 which in turn rotates bevel gear 110. As bevel gear 110 rotatively meshes with bevel gear 50, clockwise rotation is imparted to 75 sleeve 26 and accordingly to containers 13 and

selector wheel 51. After the desired container is selected, knob 41 is turned in a clockwise direction and through the action of cam 47 on disgorge lever 48, an article 31 is delivered from its container 13 into delivery chute 30 and thence to delivery pocket 16 from which it may be obtained. When knob 41 is released, spring 58 returns the knob to its normal position and at the same time the locking mechanism is restored to a locked condition. 10

However, if a leather slug or the like, which will not pass through scavenger 82 (Figure 5) is deposited therein, the machine will not be unlocked and when an attempt to operate the machine is made the scavenger will be flicked open 15 as often as knob 41 is turned in one direction or another and accordingly the leather slug will be rejected and the coin track left unobstructed.

It can now be seen that I have provided a vending machine wherein a multitude of different kinds of vendable articles may be displayed and selected for delivery by the turning of an operating knob in one direction. It may also now be seen that by the turning of this same operating knob in the opposite direction delivery of the 20 selected article is readily effected. 25

Accordingly there has here been provided a vending machine in which the various objects hereinabove set forth together with many other thoroughly practical advantages are successively 30 achieved. 35

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. The combination with a vending machine 40 in which a movable container includes a plurality of compartments capable of holding different kinds of articles, each compartment being capable of holding a plurality of superimposed articles; of an operating apparatus including compartment selecting mechanism, delivery effecting mechanism, and means operable in one direction to actuate said selecting mechanism to make an optional choice of any one of said compartments and place the chosen compartment in delivery 45 position, said means being operable in the opposite direction to effect positive delivery of one article from the chosen compartment by displacing the article therefrom. 50

2. The combination with a vending machine in 55 which a movable container includes a plurality of compartments capable of holding different kinds of articles, each compartment being capable of holding a plurality of superimposed articles; of an operating apparatus including compartment selecting mechanism, delivery effecting mechanism, and means rotatable in one direction to actuate said selecting mechanism to make an optional choice of any one of said compartments and place the chosen compartment in delivery 60 position, said means being rotatable in the opposite direction to effect positive delivery of one article from the chosen container by displacing the article therefrom. 65

3. The combination with a vending machine 70 in which a movable container includes a plurality of compartments capable of holding different kinds of articles, each compartment being capable of holding a plurality of superimposed articles; of an operating apparatus including com- 75

partment selecting mechanism, delivery effecting mechanism including an ejector, and means operable in one direction to actuate said selecting mechanism to make an optional choice of 5 any one of said compartments and place the chosen compartment in delivery position, said means being operable in the opposite direction to actuate said ejector to engage one article in the chosen container and displace it therefrom 10 for delivery thereof.

4. The combination with a vending machine in which a movable container includes a plurality of compartments capable of holding different kinds of articles, each compartment being 15 capable of holding a plurality of superimposed articles; of an operating apparatus including compartment selecting mechanism, delivery effecting mechanism, means operable in one direction to actuate said selecting mechanism to 20 make an optional choice of any one of said compartments and place the chosen compartment in delivery position, said means being operable in the opposite direction to effect positive delivery of one article from the chosen compartment by 25 displacing the article therefrom, and means for preventing delivery operation of said operable means when the chosen container is empty.

5. The combination with a vending machine in which a movable container includes a plurality 30 of compartments capable of holding different kinds of articles, each compartment being capable of holding a plurality of superimposed articles; of an operating apparatus including compartment selecting mechanism, delivery effecting mechanism, means operable in one direction to actuate 35 said selecting mechanism to make an optional choice of any one of said compartments and place the chosen compartment in delivery position, said means being operable in the opposite direction 40 to effect positive delivery of one article from the chosen compartment by displacing the article therefrom, and means forming a delivery chute for delivering to the purchaser the article displaced.

45 6. The combination with a vending machine in which a movable container includes a plurality of compartments capable of holding different kinds of articles, each compartment being capable of holding a plurality of superimposed 50 articles; of an operating apparatus including compartment selecting mechanism, delivery effecting mechanism, means operable in one direction to actuate said selecting mechanism to make an optional choice of any one of said compartments and place the chosen compartment in 55 delivery position, said means being operable in the opposite direction to effect positive delivery of one article from the chosen compartment by displacing the article therefrom, and means 60 operatively associated with said selecting mechanism for limiting movement of said container to one direction of movement only.

7. The combination with a vending machine in which a movable container includes a plurality 65 of compartments capable of holding different kinds of articles, each compartment being capable of holding a plurality of superimposed articles; of an operating apparatus including compartment selecting mechanism, delivery effecting mechanism, and means operable in one direction to actuate said selecting mechanism to make an optional choice of any one of said compartments 70 and place the chosen compartment in delivery position, said means being operable in the opposite direction to effect positive delivery of one article from the chosen compartment by displacing the article therefrom, said operable 75 means including a shaft, ratchet means associated with said shaft, and pawl means engageable with said ratchet means to prevent selective operation of said operable means after delivery operation thereof has been commenced.

delivery of one article from the chosen compartment by displacing the article therefrom, said means including a clutch having parts automatically engageable in one direction of operation of said means to move said container, said clutch 5 also including parts automatically engageable in the opposite direction of operation of said operable means to effect actuation of said delivery mechanism, said first-mentioned clutch parts being disengaged during the engagement of said 10 second-mentioned parts.

8. The combination with a vending machine in which a movable container includes a plurality of compartments capable of holding different kinds of articles, each compartment being 15 capable of holding a plurality of superimposed articles; of an operating apparatus including compartment selecting mechanism, delivery effecting mechanism, means operable in one direction to actuate said selecting mechanism to make 20 an optional choice of any one of said compartments and place the chosen compartment in delivery position, said means being operable in the opposite direction to effect positive delivery of one article from the chosen compartment by displacing the article therefrom, said means including a clutch having parts automatically engageable in one direction of operation of said 25 means to move said container, said clutch also including parts automatically engageable in the 30 opposite direction of operation of said operable means to effect actuation of said delivery mechanism, said first-mentioned clutch parts being disengaged during the engagement of said second-mentioned parts, and spring means constantly 35 urging said clutch into driving engagement during its selecting operation.

9. The combination with a vending machine in which a movable container includes a plurality of compartments capable of holding different kinds 40 of articles, each compartment being capable of holding a plurality of superimposed articles; of an operating apparatus including compartment selecting mechanism, delivery effecting mechanism, and means operable in one direction to actuate 45 said selecting mechanism to make an optional choice of any one of said compartments and place the chosen compartment in delivery position, said means being operable in the opposite direction to effect positive delivery of one 50 article from the chosen compartment by displacing the article therefrom, said selecting mechanism including a part operable to maintain the selected container in delivery position after selection thereof.

55 10. The combination with a vending machine in which a movable container includes a plurality of compartments capable of holding different kinds of articles, each compartment being capable of holding a plurality of superimposed articles; of an operating apparatus including compartment selecting mechanism, delivery effecting mechanism, and means operable in one direction to actuate said selecting mechanism to make an optional choice of any one of said compartments 60 and place the chosen compartment in delivery position, said means being operable in the opposite direction to effect positive delivery of one article from the chosen compartment by displacing the article therefrom, said operable 65 means including a shaft, ratchet means associated with said shaft, and pawl means engageable with said ratchet means to prevent selective operation of said operable means after delivery operation thereof has been commenced.

11. The combination with a vending machine in which a movable container includes a plurality of compartments capable of holding different kinds of articles, each compartment being capable of holding a plurality of superimposed articles; of an operating apparatus including compartment selecting mechanism, delivery effecting mechanism, means operable in one direction to actuate said selecting mechanism to make an optional choice of any one of said compartments and place the chosen compartment in de-

livery position, said means being operable in the opposite direction to effect positive delivery of one article from the chosen compartment by displacing the article therefrom, said operable means including a cam, and an ejector arm operatively associated with said cam upon operation thereof in delivery direction to effect the displacement of said article from the chosen compartment. 5

GILBERT J. SCOFIELD. 10
